United States Patent Office

Des. 197,642
Patented Mar. 10, 1964

197,642

BUILDING

Ross E. Garrett, Chicago, Ill., assignor to Kesk, Inc.,
New Orleans, La., a corporation of Delaware

Filed Mar. 25, 1963, Ser. No. 74,122

Term of patent 14 years

(Cl. D13—1)

FIG. 1 is a perspective of a building showing my new design;

FIG. 2 is a front elevational view thereof; and

FIG. 3 is a reduced scale top plan view thereof.

I claim:

The ornamental design for a building, as shown.
